UNITED STATES PATENT OFFICE.

WILLIAM MCGILVERY, OF DULUTH, MINNESOTA.

CAMP TABLE.

Application filed March 15, 1926. Serial No. 94,656.

This invention relates to camping tables and has particular reference to such a table particularly designed for use in any of the numerous tourist camps throughout the 5 country.

The principal object of the invention is to provide such a table particularly applicable to the use of tourists, and one that may be so arranged that it will hold a tourist's cooking equipment and dishes safely during the nighttime, or at times other than 10 when the device is used as a table.

Other objects and advantages will appear in the further description of the invention.

15 Referring now to the accompanying drawing, forming part of this application, and wherein like reference characters indicate like parts:

Figure 1 is a central section of the device 20 showing the sides and ends folded for use as a common table, and one of the legs folded up as it would appear when the device is to be moved;

Figure 2 is a fragmental top plan view of 25 the device as it would appear with the ends and one side raised to provide a wind or weather shield and the other side extended;

Figure 3 is a side view of Figure 2;

Figure 4 is a bottom plan view of the 30 table, and

Figure 5 is a fragmental top plan view.

The table top comprises a rectangularly shaped board 1, which may be of any size desired and best suited for the purpose, to 35 either side of which are hinged the extension leaves 2 and 3, the extreme free ends of which are practically in the form of barefaced tenons, so that when they are folded over one upon the other, as shown in Figure 1 they 40 form a scarf joint with the surface of the leaves or wings in the same plane.

To the ends of the table top 1 are hinged the triangularly shaped wings 4 and 5' and these are adapted to be swung downwardly 45 and inwardly, up against the bottom of the table top, as indicated in Figure 1.

The legs consist of screw threaded rods 5, 50 pivotally mounted within the brackets 6, which are fixed to the bottom of the table top. Extension legs 7 are provided which 55 consist of interiorly screw threaded tubes which screw threadedly engage the legs 5, so that by screwing or unscrewing the extension legs 7 the table top may be made to assume a level position regardless of any irregularities in the ground surface. The

legs may be folded upwardly against the bottom of the table top, as indicated in Figure 1, for transporting the device, and to hold the same in such position, as well as in upright position when functioning as a table leg, there is shown a collar 8 for each leg, this collar being adapted to slip over the leg and onto the bracket 6 just below its pivotal connection with the leg, and is then secured by 60 the set screw 9, which prevents the leg from any pivotal movement when in either of the positions illustrated in Figure 1.

I have shown in the wing 2 a notched out portion 10 which communicates with a longitudinal slot extending from the portion 10 out through the end of the wing 2. This slot registers when the wings are folded together as in Figure 1 with a like slot 11 in the wing 70

3 and in these slots may reciprocate the locking key 12 one end of which is upturned forming a convenient means for reciprocating the same, and when the key extends into the slot 11 it holds the wings tightly down 75 against the table top, and when in this position the table is ample for two persons. However when more room is desired the wings may be made to function as extension wings as indicated in Figure 3. Whenever 80

protection is needed from high winds or other interference from the elements the ends 85 4 and 5 may be raised to a vertical position and for example the wing 3 swung up to rest against the edge of the end wings, as indicated in Figure 2. During the nighttime, or 90 at times when the device is used other than as a table, both of the side wings may be made to rest against the edge of the wings 4 and 5, as indicated in Figure 3, which will 95 completely house in the average tourist's cooking equipment so that he will not have to pack the same away at night and then have to get it out again in the morning. A hole 100

13 may be made in the end of the wing 3, so that, as shown in Figure 3, the key 12 may 105 extend through same and made secure in that position by any suitable padlock or other locking means. A pivotal brace is indicated at 14 which may support the side wings when used as extensions of the table top.

From the foregoing it is apparent that I 110 have devised a camping table which meets a great many of the requirements of the auto tourist. Of course various modifications of structure and arrangement of parts may be resorted to without departing from the spirit of the invention.

Having thus described my invention, what I claim and desire to secure by Letters Patent is:

The combination with a foldable table of the class described having a top comprising a central portion to which foldable wing portions are attached, of two of said wing por-

tions overlapping each other and lying in the same plane on top of the central portion, and means for holding said wing portions in overlapping relation.

In testimony whereof I hereunto affix my signature.

WILLIAM McGILVERY.
